TWO-STROKE MOTOR

Henri Convert, Lyon, France

Application July 18, 1945, Serial No. 605,760
In France March 1, 1944Section 1, Public Law 690, August 8, 1946
Patent expires March 1, 1964

6 Claims. (Cl. 123—73)

1

My invention relates to a two stroke motor the particular design of which bestows on it special properties chiefly from the standpoint of efficiency.

This motor is essentially characterized in that it comprises a differential double piston and cylinder group, the upper cylinder of small bore being used for feeding while the lower cylinder of higher bore provides the driving stroke, the common piston formed as a double cylinder being hollow and ensuring through its central channel the transfer under a pressure higher than normal, of the carburetted mixture into the lower cylinder providing the driving stroke.

Other features are associated with my novel assembly of two cylinders for furthering its operation. These features are chiefly as follows:

(a) The rich gases are sucked into the part of smaller diameter of the upper cylinder, through a port uncovered at the end of its downward stroke by the corresponding head portion of the piston and are during the upward stroke of the piston urged back into an annular chamber in which they are submitted to a preliminary compression.

(b) The air required for forming the mixture enters the casing of the motor through peripheral ports uncovered at the end of the upward stroke by the skirt of the body portion of greater cross-section of the piston and are compressed during the downward movement.

(c) The head portion of the piston comprises large openings opening into its central channel and ensuring on one hand at the end of the upward stroke the transfer into the casing of the rich gases which are then admixed with air and on the other hand at the end of the downward stroke the transfer into the cylinder providing the driving stroke of the air and gas mixture.

(d) The exhaust gases are removed through a number of ports distributed at the base of the periphery of the cylinder which allows reducing the height, said ports being uncovered at the end of the downward stroke by the upper part of the piston body.

The invention will be well understood by referring to appended diagrammatic drawing and to the complementary description relating thereto, said drawing and its description being obviously given only by way of an example and in no manner in a limitative manner.

In said drawings:

Figs. 1 and 2 are two views in elevational axial cross-section of the motor with the piston respectively at its higher and lower dead points.

2

Fig. 3 is, at a larger scale, a horizontal cross-section through line 3—3 of Fig. 2.

According to my invention, this motor comprises a piston constituted by two parts of different diameters: a head 1 and a body 2 moving inside a double cylinder comprising two corresponding bores respectively at 3 and at 4. This piston is connected in the usual manner with a connecting rod 5 pivotally secured to a crank-shaft 6 rotating inside a fluid tight casing 7.

This piston 1—2 is tubular and is provided with a central channel 8 communicating through its base with the casing while ports 9 provided at the periphery of the piston head 1 open into the upper end of the bore.

The cylinder 3 is provided at its lower end with a pipe 10 for the admission of rich gases and throughout its length with a lining 12 showing at its upper part ports 13 which put the cylinder in communication with an annular chamber 14.

The cylinder 4 inside which the carburetted mixture is ignited by means of the spark plug 15 is provided with ports 16 distributed throughout its periphery for the escape of the burnt gases opening into the exhaust collector 17 on one hand and with ports 18 for the admission of fresh air into the casing 7 on the other hand.

Segments, respectively shown at 19 and 20, ensure the fluid-tightness of the pistons 1, 2, in their cylinders 3 and 4.

The operation of this motor is as follows:

First stroke

The piston moving downwards when the gases expand in the cylinder 4, a reduced pressure prevails inside the cylinder 3 above the piston head 1 while the gases inside the casing 7 are compressed.

A little before the end of the downward stroke, the lower piston 2 uncovers the exhaust ports 16 while the upper piston 1 uncovers above its segments 19 the admission pipe 10 for the admission of the rich gases coming from the carburettor, which allows the filling of the cylinder 3. On the other hand, at this moment, the head or upper piston puts in communication through its transfer ports 9 the motor casing 7 with the upper part of the cylinder 4, which ensures thus the filling of the driving cylinder to its capacity. The skirt of the piston 2 closes at this moment the ports 18 admitting air into the casing.

Second stroke

During the upward movement of the piston, the transfer ports 9 of the head 1 are closed at the same time as the latter closes the opening

of the pipe 10 admitting the rich gases, after which the exhaust ports are closed in their turn by the piston body 2.

The compression of the explosive mixture is then performed inside the driving cylinder 4 while the rich gases are forced at low pressure out of the cylinder 3 into the chamber 14 through the ports 13. As soon as the transfer ports 9 arrive in front of said ports 13, these rich gases are transferred into the casing 1 through the central channel 8 while the skirt of the piston 2 uncovers the ports 13 so as to allow an admission of fresh air mixing with the rich gases.

A little before the higher dead point, the carburetant mixture compressed in the cylinder 4 is ignited by the spark plug 15, and its explosion urges the system downwards so as to initiate the driving stroke, at the same time as the piston is started again on its first stroke.

The advantages provided by such a motor are easy to understand.

There is in fact an overfeed by reason of the very shape of the piston, the gases being admitted into the cylinder body at a pressure above the usual pressure.

The fresh gases which have only to pass through the piston wall along passages the cross section of which is much greater than is usual, arrive in a very short time inside the cylinder.

The cooling is considerably improved by the intense circulation of fresh gases inside the piston by reason of the admission of the gaseous mixture, at the head of the driving cylinder.

The self ignition is thus prevented, which allows the adoption of high compression rates.

On the other hand, the direct admission of rich gases is more unconstrained and more precise than in any extant motor, which leads to a reduction in consumption.

Moreover for a same length of stroke, the expansion is more considerable than in a normal motor by reason of the small height which it is possible to give to the exhaust ports which receive moreover a very high total cross section, which allows the obtention of very high running speeds.

It should be noted finally that these advantages are by no means obtained at the expense of the simplicity of the operation or by the introduction of devices or mechanisms which are costly to establish. The cost price of this motor is as a matter of fact substantially comparable with that of any conventional motor.

My improved motor may also be designed for injection feed.

Lastly, as obvious and as apparent moreover from the above disclosure, my invention is by no means limited to the single form hereinabove nor to that of its different parts nor to their relative positioning as shown, it covers on the contrary all the modifications in execution thereof.

The manner of feeding the motor as described is not the only manner suitable for said motor. Nothing prevents the combustion mixture from being admitted both through the admission means 10 and 16, provided the ports 13 open inside a collecting pipe similar to the pipe 17.

What I claim is:

1. A two stroke motor comprising a cylinder including two parts of different radii, a hollow stepped piston adapted to reciprocate in said cylinder, the narrower part of which forms a combustion chamber, a casing communicating with the inside of the piston and closing the base

of the larger part of the cylinder, means for feeding a part of the combustible mixture into the outer end of the narrower part of the cylinder when the piston has moved outwardly, means passing through the inner end of the outer wall of the piston at a location angularly shifted with said feeding means for transferring said part of the combustible mixture through the hollow piston from the compression chamber into the casing when the piston has returned inwardly and subsequently transferring the mixture through the piston from the casing into the larger part of the cylinder when the piston has moved again outwardly and exhaust means communicating with the larger part of the cylinder.

2. A two stroke motor comprising a cylinder including two parts of different radii, a hollow stepped piston adapted to reciprocate in said cylinder, the narrower part of which forms a combustion chamber, a casing communicating with the inside of the piston and closing the base of the larger part of the cylinder, means for feeding a part of the combustible mixture into the outer end of the narrower part of the cylinder when the piston has moved outwardly, means for admitting directly the remaining component of the mixture into the casing when the piston has returned inwardly, means passing through the inner end of the outer wall of the piston at a location angularly shifted with said feeding means for transferring said part of the combustible mixture through the hollow piston from the compression chamber into the casing when the piston has returned inwardly and subsequently transferring the two portions of the mixture together through the piston from the casing into the larger part of the cylinder when the piston has moved again outwardly and exhaust means communicating with the larger part of the cylinder.

3. A two stroke motor comprising a cylinder including two parts of different radii, a hollow stepped piston adapted to reciprocate in said cylinder, the narrower part of which forms a combustion chamber, a casing communicating with the inside of the piston and closing the base of the larger part of the cylinder, unrestricted permanently open means for feeding a part of the combustible mixture into the outer end of the narrower part of the cylinder when the piston has moved outwardly, unrestricted permanently open means for admitting directly the remaining component of the mixture into the casing when the piston has returned inwardly, unrestricted permanently open means passing through the inner end of the outer wall of the piston at a location angularly shifted with said feeding means for transferring said part of the combustible mixture through the hollow piston from the compression chamber into the casing when the piston has returned inwardly and subsequently transferring the two portions of the mixture together through the piston from the casing into the larger part of the cylinder when the piston has moved again outwardly and exhaust means communicating with the larger part of the cylinder.

4. A two stroke motor comprising a cylinder including two parts of different radii, a hollow stepped piston adapted to reciprocate in said cylinder, the narrower part of which forms a combustion chamber, a casing communicating with the inside of the piston and closing the base of the larger part of the cylinder, means for feeding a part of the combustible mixture into the nar-

rower part of the cylinder when the piston has moved outwardly, means for admitting directly the remaining component remainder of the mixture into the casing when the piston has returned inwardly, means passing through the inner end of the outer wall of the piston for transferring said part of the combustible mixture through the hollow piston from the compression chamber into the casing when the piston has returned inwardly and subsequently transferring the two portions of the mixture together through the piston from the casing into the larger part of the cylinder when the piston has moved again outwardly and exhaust means communicating with the larger part of the cylinder.

5. A two stroke motor comprising a cylinder including two parts of different radii, a hollow stepped piston adapted to reciprocate in said cylinder, a ring shaped compression chamber surrounding the inner end of the narrower part of the cylinder and communicating therewith, a casing communicating with the inside of the piston and closing the base of the larger part of the cylinder, means for feeding a part of the combustible mixture into the outer end of the narrower part of the cylinder when the piston has moved outwardly, means for admitting directly the remaining component of the mixture into the casing when the piston has returned inwardly, means passing through the inner end of the outer wall of the piston at a location angularly shifted with said feeding means for transferring said part of the combustible mixture through the hollow piston from the compression chamber into the casing when the piston has returned inwardly and subsequently transferring the two portions of the mixture together through the piston from the casing into the larger part of the cylinder when the piston has moved again outwardly and exhaust means communicating with the larger part of the cylinder.

6. A two stroke motor comprising a cylinder including two parts of different radii, a hollow

- stepped piston adapted to reciprocate in said cylinder, the narrower part of which forms a combustion chamber, a casing communicating with the inside of the piston and closing the base of the larger part of the cylinder, means for feeding a part of the combustible mixture into the outer end of the narrower part of the cylinder when the piston has moved outwardly, means for admitting directly the remainder of the mixture into the casing when the piston has returned inwardly, means passing through the inner end of the outer wall of the piston at a location angularly shifted with said feeding means for transferring said part of the combustible mixture through the hollow piston from the compression chamber into the casing when the piston has returned inwardly and subsequently transferring the two portions of the mixture together through the piston from the casing into the larger part of the cylinder when the piston has moved again outwardly and exhaust means constituted by a number of ports of reduced height at the outer periphery of the larger part of the cylinder and adapted to be uncovered at the end of the outward movement of the piston by the larger part thereof.
